UNITED STATES PATENT OFFICE.

MARTIN BECKER, OF MACDONA, TEXAS.

MAIL-BAG CATCHING AND DELIVERING DEVICE.

1,206,654.

Specification of Letters Patent. Patented Nov. 28, 1916.

Application filed May 1, 1914. Serial No. 835,703.

To all whom it may concern:

Be it known that I, MARTIN BECKER, a citizen of the United States, residing at Macdona, in the county of Bexar and State 5 of Texas, have invented new and useful Improvements in Mail-Bag Catching and Delivering Devices, of which the following is a specification.

This invention relates to a mail bag 10 catcher and delivering device.

The primary object of the invention is the provision of an apparatus of this character wherein mail bags can be automatically exchanged between a moving train 15 and a station, the device on the car and at the station being readily reversible so that an exchange of bags can be accomplished irrespective of the direction of travel of the train.

20 An object of the invention is the provision of an apparatus of this character wherein the device is of novel form to assure positiveness in exchanging mail bags and also to render the same serviceable and durable.

25 With these and other objects in view, the invention consists in the construction, combination and arrangement of parts as will be hereinafter fully described, illustrated in the accompanying drawing and pointed out in the claims hereunto appended.

30 In the drawing: Figure 1 is a plan view of the device with portions in sections. Fig. 2 is a view similar to Fig. 1 showing the parts in another position. Fig. 3 is a sectional view on the line 7—7 of Fig. 2. Fig. 4 is a sectional view on the line 8—8 of Fig. 1.

35 My invention consists of a turn table 26 formed with an outwardly extending arm 27 projecting from one side thereof, while diametrically opposite this arm are outwardly divergent catching arms 28. The space between the arms connects with a recess 29 formed in the turn table. Upon opposite sides of the recess 29 are grab doors 30 fitted with a counterseat 31 formed in the table 26, jaws 30 being formed with handle levers 32 that project beyond the peripheral

turn table 26 for permitting the manual 50 opening of the jaws after the automatic closing thereof. One of the jaws 30 supports in a pivotal manner a trip latch 33 which projects across the recess 29 and engages a shoulder 34 on the other jaws 30 to 55 normally hold the jaws open, the jaws being acted upon by means of a coiled extension spring 35 surrounding a guide pin 36 passed through the elongated slots 37 in the levers 32 of the jaws and engaged in the table 26. 60 The springs 35 are designed to automatically close the jaws 30 on the tripping of the latch 33 by the impact between the bag and the trip with the result that the jaws immediately grip the sack. At the outer 65 end of the arm 27 is a hook 38 coöperating with a spring pressed keeper 39, the hook 38 being provided for the purpose of supporting a mail bag for delivering it to a 70 passing train.

75 From the foregoing description it will be seen that a mail bag may be effectively caught and substantially held against movement and the stress created by the impact may be properly taken care of by the co-operation between the jaws and circuit wheels of the turn table.

Having thus described my invention, what I claim is:

1. A mail bag catcher comprising a table 80 formed with rigid outwardly divergent catching arms and with an opening between the catching arms, grab jaws pivotally mounted on the table and having hand levers arranged to move within recesses in 85 said table, means acting on the levers for automatically closing grab jaws and a trip latch pivoted to one of the grab jaws and engaging with the other for normally holding the said jaws open and bridge the opening in the table.

2. A mail bag catcher comprising a table 90 formed with an opening and a recess the wall of which being arcuate shaped at two-spaced points, grab jaws pivotally mounted 95 in the recess and having arcuate shaped hand levers adapted to move in engagement with the arcuate portion of the recess wall

for distributing the stress to which the pivot of the jaws are subjected, means acting upon the levers for automatically closing the grab jaws and a trip latch arranged to be struck by the mail bag, said trip being pivotally mounted upon one jaw and having a detachable engagement with the other jaw.

In testimony whereof I affix my signature in presence of two witnesses.

MARTIN BECKER.

Witnesses:
